DESIGN FOR A CARPET SWEEPER

Charles A. Anderson, New Rochelle, N. Y., assignor to Gotham Pressed Steel Corporation, New York, N. Y., a corporation of New York

Application August 11, 1937, Serial No. 70,996

Term of patent 3½ years

To all whom it may concern:

Be it known that I, Charles A. Anderson, a citizen of the United States and resident of New Rochelle, in the county of Westchester and State of New York, have invented a new, original, and ornamental Design for a Carpet Sweeper, of which the following is a specification, reference being had to the accompanying drawing, forming a part thereof:

Fig. 1 is a front perspective view of a carpet sweeper showing my new design; and

Fig. 2 is an end elevational view of the same.

I claim:

The ornamental design for a carpet sweeper, as shown.

CHARLES A. ANDERSON.
